FILTERING DEVICE USED IN CONNECTION WITH INTERNAL COMBUSTION ENGINES, OR THE LIKE

William Mautner, Newark, N. J.

Application October 25, 1935, Serial No. 46,802

2 Claims. (Cl. 210—165)

The subject-matter of the present invention relates generally to the art of collection and separation of materials, but more specifically has to do with a device for the arresting and collection of foreign materials present in the cooling fluid of the circulatory system of an internal combustion engine, or the like.

Primarily, the object of the invention is to provide a device of the above-mentioned character which may be conveniently installed between the outlet pipe of the water jacket of an internal combustion engine, or the like, and the inlet in the tank at the top of a radiator, without materially altering the present constructions.

Another object is to provide a device adapted to receive and house a trap element suitably constructed to receive foreign materials arrested by a screen borne by the upper end of said element.

A still further object is to provide means serving as a guide whereby said trap element and its screen element may be positively arranged in a predetermined position within the tubular portion of the device.

Still another aim of the invention is to produce a device that may be attached to the tank of a radiator by different ways and methods.

Other objects and advantages will be apparent as the nature of the invention is better set forth, and it will be understood that changes within the scope of the claims may be resorted to without departing from the spirit of the invention.

In the drawings:

Figure 1 is an elevation illustrating one method of connecting my invention to the cooling system of an internal combustion engine.

Fig. 2 is a central longitudinal sectional view of the device.

Fig. 3 is an elevation of the trap element removed from the device.

Fig. 4 is a view similar to Fig. 2, but slightly reduced in scale, and showing the casing portion of the device.

Fig. 5 is a fragmentary elevation of the lower end of the tubular extension of the device and showing a closure applied to the extremity thereof and means for holding said closure in position.

Fig. 6 is an inverted plan view of said tubular extension with the closure removed.

Fig. 7 is a central longitudinal sectional view of another form of the device.

Fig. 8 is a bottom plan view thereof.

Fig. 9 is an inverted plan view of the lower end of the tubular portion shown in Fig. 7.

Fig. 10 is an elevation of the trap element shown in connection with Fig. 7.

Figs. 11, 12 and 13 show different methods of attaching the device to the upper tank of a radiator.

Referring to said drawings, 5 indicates generally the casing shown in Figs. 1, 2 and 4, said casing embodying tubular end portions 6 and 7 adapted for connection with the inlet pipe 8 of a radiator 9 and the outlet pipe 10 of the water jacket 11 of an internal combustion engine, respectively. Said casing also includes a tubular extension 12 disposed angularly with respect to the longitudinal axis of said tubular portions, as shown in Fig. 2, and being adapted to receive a trap member 13 having a bottom 14, the wall of said member being cut away to present an opening 15 which aligns with the passageway in said tubular end portions 6 and 7 when the parts are assembled as in Fig. 2. Upon inspection of Figs. 2 and 3 it will be noted that the upper end of said member 13 is cut on the bias to support a screen 16. As shown in Fig. 1 the end portion 6 is coupled to the inlet pipe 8 by means of suitable rubber tubing 17, whilst the end portion 7 is joined to the outlet pipe 10 by means of rubber tubing 18, suitable clamping members 19 and 20 being resorted to. The casing is preferably made of rust-proof material and in view of the opening 15 in said trap element 13 the circulating cooling medium has a clear passage through the tubular portions 6 and 7, said screen 16 interrupting and arresting foreign substances in said cooling medium and preventing the passage thereof to said radiator, thus preventing clogging, or the like. As shown in Fig. 2 said screen 16 is inclined at an acute angle to the transverse plane of said tubular portion and in this position it provides for the deposit of foreign substances and their subsequent descent into said trap member 13, said member having a bottom 14 for retaining said substances.

In assembling the device for use, the trap member 13 is pushed upwardly into said extension 12 and to assure that the screen 16 is properly positioned within the casing, the wall of said extension is provided with a rib-like formation 21 which cooperates with grooves 22 in said trap member 13, in an obvious manner. The bottom 14 of said member 13 is provided with a handle 23 which facilitates the entry and removal of said trap member and the latter is finally held in the position indicated in Fig. 2 by means of a cap 24 and a washer 25. Said cap 24 may be threaded

to engage the threaded portion 26 of said extension 12.

If desired, the aforesaid threaded engagement of the cap may be dispensed with and in lieu thereof a cap 27 may be secured to the end face of the tubular extension 12, (see Fig. 5), by means of a bail 28, the latter having its ends pivotally carried by said extension, as shown at 29 and 30, the bight portion 31 of said bail engaging the abutment 32 to assure a tight fit. When the bail is swung to the position indicated by dotted lines in Fig. 5, the cap may be removed. To properly mount the trap member with its screen at the necessary position, I propose to provide slots 33 which receive the side portions of the handle-like element 34, as shown in Fig. 6. The trap member will also be provided with a certain marking, as indicated at 35 in Fig. 3, to assure that the screen will be properly positioned.

When the usual symptoms of a clogged strainer or screen make themselves apparent, the cap 26, or the cap 27, may be removed and the trap element 13 can be drawn out of the extension 12 for cleaning so that all materials in said member and all foreign matter clogging said screen are removed and the trap member replaced for further service.

In Fig. 7 the casing 36 is provided with end portions 37 and 38, the former portion being provided with a flange 39 which is suitably riveted or soldered to the tank 40 of the radiator 41, as shown in Fig. 11, whilst the end portion 38 is connected to the water jacket 42 by means of rubber tubing 43 and clamps 44. Other methods of securing the end portion 37 to the tank 40 may be resorted to, as for instance said end portion may be provided with a flange 45 and bolted to a flange 46 extending from the tank 40, as shown in Fig. 12. Said flange 46 may be soldered or otherwise fastened to said tank 40. In Fig. 13, said end portion 37 is provided with threads 47 to engage a threaded nipple 48 suitably fastened to said tank 40. Reverting to Fig. 7 it will be noted the tubular extension 48 extends downwardly from said casing 36 and receives the trap element 49, having a bottom 50, the upper end being cut on the bias and carrying a screen 51 disposed in the passageway of said casing 36. The rear of said element 49 is cut away at 52 so the cooling medium may flow uninterruptedly through said passageway. Said screen 51 arrests the passage of foreign substances in said cooling medium which drop into the trap element 49 for subsequent removal. In order to properly position said trap element in the extension 48, the latter is provided with diametrically opposed slots 53, see Fig. 9, to receive the ends of the handle-like element 54 carried by the bottom 50 of said trap element 49. The rear portion of said element 49 may be provided with an arrow 55 to avoid confusion in assembling said element.

After said trap element 49 has been inserted within the extension 48, a gasket 56 is applied and the cap 57 is secured in position by means of the bail 58 pivotally carried by said extension

48, as shown. The bight portion of said bail is snapped over the abutment 59 in the same manner as pointed out hereinbefore. If desired, the end of said extension 48 may be threaded to engage a threaded cap of the type shown in Fig. 2. 5

The use of the device assures that the cooling medium will circulate in a satisfactory manner and that all foreign substances will be restrained from entering the top tank of a radiator and the tubes thereof, thus preventing overheating of the 10 engine or an impairment to the satisfactory operation of the cooling system.

I claim:

1. A filtering device for use in conjunction with the cooling system of an internal combustion engine, or the like, said device comprising a casing embodying a tubular portion, the ends thereof adapted for connection with the inlet of a radiator and the outlet of the water jacket of an engine, said casing also including a tubular extension disposed angularly with respect to said tubular portion, said extension having a rib-like formation extending inwardly from the wall thereof and longitudinally of said extension, a removable trap member positioned within said extension, 25 and having a bottom, the wall of said member being cut away to present an opening registering with the passageway in said tubular portion to permit the course of the cooling liquid therethrough, said trap member having its side wall 30 grooved to register with the rib of said extension to assure a predetermined positioning of said trap member within said casing, and a screen borne by the upper end of said trap member and spanning said passageway to arrest the travel of foreign material therethrough.

2. A filtering device for use in conjunction with the cooling system of an internal combustion engine, or the like, said device comprising a casing embodying a tubular portion, the ends thereof adapted for connection with the inlet of a radiator and the outlet of the water jacket of an engine, said casing also including a tubular extension disposed angularly with respect to said tubular portion, the lower portion of said extension being internally grooved, a removable trap member positioned within said extension and having a bottom, the wall of said member being cut away to present an opening registering with the passageway in said tubular portion to permit the course of the cooling liquid therethrough, a handle-like element borne by the bottom of said trap element the sides thereof being receivable within the grooves of said extension to assure a predetermined positioning of said trap element within said casing, a screen borne by the upper end of said trap element and spanning said passageway to arrest the travel of foreign material therethrough, a closure for the bottom of said extension and having an abutment, and a bail pivotally supported by said extension and engageable with said abutment to secure said closure to said extension.

WILLIAM MAUTNER. 65
